BRASSIÈRE

Charles Gubernick, Brooklyn, N. Y.

Application June 30, 1948, Serial No. 147,307

Term of patent 3½ years

(Cl. D20—4)

To all whom it may concern:

Be it known that I, Charles Gubernick, a citizen of the United States, residing at 84 Moore Street, Brooklyn, New York, in the county of Kings and State of New York, have invented a new, original, and ornamental Design for Brassières, of which the following is a specification, reference being had to the accompanying drawing, forming part thereof.

The Figure 1 is a front view of a brassière, showing my new design.

The Figure 2 is a top view showing the contour of the brassière.

I claim:

The ornamental design for a brassière, as shown.

CHARLES GUBERNICK.
